UNITED STATES PATENT OFFICE

2,315,149

X-RAY MACHINE

Elmer Jared Bliss, Boston, Mass.

Application June 29, 1940, Serial No. 343,202

9 Claims. (Cl. 250—50)

This invention relates to X-ray machines and more specifically contemplates cabinets incorporating X-ray apparatus adapted to take a radiograph or to fluoroscope the feet of a person, standing on a platform comprising a part of the cabinet, to facilitate the proper fitting of shoes.

Most ready-made shoes are classified as to size by only a few measurements, as for example, length and width, and accordingly measurement of the feet of a person to be fitted is ordinarily confined to the taking of those dimensions. However, the exact shape of the feet may vary greatly without reflecting proportionate variations in such measurements. Another consideration in preselecting the size of shoes most likely to afford comfort and adequate support of the feet is that slight differences in the relative size of a person's feet may require shoes of slightly larger dimensions than would be indicated by usual measurements. Moreover ready-made shoes are seldom of exactly the same size, so that it is impossible to obtain any more than a very general idea of how well a shoe will fit prior to the actual fitting.

Consequently, great care must be exercised by the customer as well as the salesman in determining by the "feel" of the shoe on the foot, whether the proper size shoe has been selected. As new shoes should fit snugly, they will to a certain extent feel uncomfortable, if only because of the stiffness of the leather. Most customers are unable to distinguish between a normal and proper constriction of the foot by a new shoe and the undue pressure or slight distortion of the foot likely to produce injury or result in permanent discomfort.

It is the general object of the present invention to provide apparatus adapted to obviate the deficiencies in conventional methods of fitting shoes, heretofore requiring excessive care of the customer and great skill by a salesman, by permitting a visual examination of the feet of the customer while wearing selected shoes.

More specifically, it is an object to provide X-ray apparatus enclosed in a cabinet embodying means to direct an X-ray beam against a platform on which the prospective customer places his feet so as to cast shadows of the bone structure and tissue of the feet on a fluorescent screen, in combination with means for viewing the screen from one or more suitable apertures in the cabinet.

Another object is the provision of a compartment, beneath a platform projecting from the bottom of a cabinet adapted to receive, selectively,

a screen for purposes of fluoroscopy, or a cassette containing film for use in making a radiograph.

Another object is to provide a cabinet of the character above alluded to, embodying a reflector for directing rays of light radiating from a fluoroscope of the feet of a person standing on a suitable platform, comprising a part of the cabinet, to viewing apertures in the top of the cabinet, so as to facilitate observation by the person whose feet are the subject of the fluoroscope.

Another object is to provide a control panel in the cabinet incorporating means for actuating a switch, controlling two different electrical circuits through the X-ray apparatus for purposes of energizing the latter for fluoroscopy and radiography, respectively, and adapted to indicate to the operator which of the circuits are energized.

Still another object is to provide a cabinet protected against stray radiation of X-rays by means restricting the primary X-ray beam to a predetermined area on the platform on which the proposed subjects of the fluoroscope or radiograph are placed, and further by means disposed below the platform to stop rays passing beyond their objective.

Still other objects and salient features of my invention, such for example as ease of operation, simplicity of design and construction of the cabinet, susceptibility to attractive appearance, and the faithful accurate representation of the foot structure in both fluoroscope and radiograph, will be apparent to those of skill in the art upon an examination of the following description read in the light of the accompanying drawing, in which:

Fig. 1 is a perspective view of the cabinet, partially broken away, illustrating particularly the external appearance of the cabinet and location of principal parts therein;

Fig. 2 is a vertical sectional view of the cabinet showing, in elevation, the container for the X-ray apparatus, the container being partially broken away to show the position of the X-ray tube;

Fig. 3 is a view in elevation partially broken away of the switch control assembly and indicator;

Fig. 4 is a broken sectional view of the screen and the carrier frame therefor, utilized in making fluoroscopes;

Fig. 5 is a broken sectional view of a cassette for holding film adapted to be substituted for the fluoroscope screen, in making a radiograph of the foot structure.

Referring to the drawing more in detail, wherein like numerals indicate similar parts throughout the several views, 7 designates generally a

cabinet comprising a floor 8, front and side walls 9 and rear wall 10. The upper portion of the cabinet is closed by a top section 11 comprising a control panel 12 sloping upwardly from the front wall to the rear wall and having sides 13 depending therefrom telescopically received within walls 9 and 10 of the cabinet proper. The top section 11 may be removed for purposes of servicing the X-ray unit hereinafter referred to.

The rear wall 10 terminates above the floor 8 of the cabinet and from its lower edge a platform 14 extends. Platform 14 comprises the top of a rearward cabinet extension 15 and is supported by rear and side walls 16 which form a light tight compartment 17.

The X-ray apparatus 18 which is largely conventional in form, is enclosed in a fluid tight case 19 mounted by suitable hangers 20 in the upper part of the cabinet with the case spaced from the rear wall 10. The X-ray tube 21, enclosed in a lead cylinder 22 to prevent uncontrolled radiation of the rays, is hung in the case by suitable means (not shown) over and adjacent an oblique rearward side 23 of case 19. The side 23 of the case is preferably arranged in a plane at right angles to a line passing through the centers of the platform 14 and tube 21. A small aperture 24 in cylinder 22 releases an X-ray beam which is directed to the platform through an opening 25 in side 23 of the case, the beam passing through the rear wall 10 of the cabinet. The X-ray apparatus 18 in the case is immersed in oil and in order to prevent oil from flowing through the opening 25, I provide a barrier 26 composed of Bakelite or other material through which the X-ray beam passes. The barrier 26 is secured in the case to wall 23 over the opening 25, a portion thereof extending closely adjacent the cylinder 22 and across the aperture 24 to minimize the quantity of oil through which the X-ray beam must pass. A lead plate 27 is secured on the exterior of side 23 of the case and is formed with an opening 28 which registers with the opening 25 in case 19. Opening 28 is carefully shaped and the plate 27 arranged on the case to mask off all of the X-rays passing through the opening 25, except those directed to platform 14. One side of the lower cabinet extension 15 is slotted as at 29 directly under platform 14 through which slot a fluorescent-screen frame 30 or a cassette 31 may be selectively inserted.

The screen frame 30, illustrated in Fig. 4, is rectangular, having inwardly extending spaced parallel sides 32 between which the screen and the associated elements about to be described are assembled for insertion as a unit into the compartment 17 through the slot 29. The screen 33 of a type well-known in the art, being preferably composed of a paper material coated with barium sulphate, is positioned on a sheet 34 of lead glass and covered by a sheet 35 of Bakelite or other material through which the X-ray will pass. The edges of the Bakelite and lead glass sheets 34 and 35 are taped or clipped together with the screen therebetween and are mounted in the frame 30, which may be made in two or more sections to facilitate this assembly. Suitable rails 36 are secured to the cabinet within the compartment adjacent the ends of the slot to support the screen frame 30 in a horizontal position.

The cassette 31 or film holder, adapted to be substituted for the screen 33 and frame 30 when a radiograph is to be made, comprises a rectan-

gular frame 37. The top 38 of the cassette is formed of Bakelite, having its edges secured to the frame. A plate 39 forming the bottom of the cassette is removably attached in the frame by suitable means, as by spring arms 40 which engage in slots 41 in sides of the frame, in a manner well known in the art. With the plate 39 removed, the film 42 is placed in the frame against the Bakelite top 38. A lead sheet 43 is then inserted into frame 37 under the film 42 to stop the X-rays passing through the film. Plate 39 is placed in the frame under sheet 43 and the spring arms 40 are engaged in the slots 41 to exert pressure through the plate against the lead sheet 43 and hold film 42 flat against the Bakelite top 38. The cassette 31 with film 42 may be slid into or out of the compartment 17 through slot 29 and is supported in the compartment by the rails 36.

The control panel 12 in the top section 11 of the cabinet is formed with three viewing apertures 44 located in the middle of the panel adjacent the rear wall 13 of the section and adjacent each of the corners of the rear wall and the side walls, respectively. A reflector 45 is mounted on the floor 8 of the cabinet directly below the centrally-located viewing aperture, and is supported by one or more props 46 at an angle suitable for reflecting light rays radiating from screen 33 below platform 14 to each of the viewing apertures 44 during a fluoroscopic examination of the feet as is hereinafter more in detail described.

Two separate electrical circuits through the X-ray apparatus are provided which energize the apparatus for fluoroscopy and in making a radiograph, respectively, as will be obvious to those engaged in the art. A double throw snap switch 47, connected in each of these circuits, is secured to the underside of a plate 48 which is in turn attached by suitable means to the underside of the control panel 12. The switch 47 is of conventional construction, being provided with a control lever 49 which extends upwardly so as to protrude through a slot 50 in plate 48. Switch 47 is operated by a knob 51 located above the control panel and secured on the upper end of a shaft 52 journalled in the panel and plate 48. One end of a lever 53 is secured to shaft 52 between the panel and plate 48. The opposite end of lever 53 is forked, bifurcations 54 thereof extending to opposite sides of switch lever 49. One end of an arm 55 is pivotally attached to lever 53 intermediate its ends. The opposite end of arm 55 is pivotally connected to an indicator plate 56 slidably in guide ways (not shown) within a dial frame 57 carried by the control panel 12. The face 58 of the dial is formed with an elongated opening 59 above the plate, with which the words "Fluoroscope" and "Radiograph," imprinted on or stamped in the indicator plate 56, are adapted to be brought selectively into registry. Thus by rotating the knob 51, the switch lever 49 may be turned to one side (i. e. to the left as shown in Fig. 3) to complete the electrical circuit by which the apparatus is energized for making a fluoroscope. In this position, the word "Fluoroscope" on the indicator plate will be registered with the opening 59 in the dial face 58 so as to be visible from the top of the cabinet and indicate the closed circuit to the operator. By turning knob 51 in the opposite direction, the forked end of lever 53 and the switch lever 49, actuated thereby, will be shifted to the right from their positions shown in Fig. 3 so as to coinci-

dentially open the electrical circuit employed in making a fluoroscope and close the circuit utilized in making a radiograph. If desired, an auxiliary switch (not shown) may also be included in the circuit by which the X-ray apparatus is energized for purposes of fluoroscopy. To prevent injury by over exposure to the X-rays in taking a radiograph, a timer, generally designated by the numeral 60, of conventional construction, is provided, and embodies a switch (not shown) controlling the circuit which energizes the X-ray apparatus when a radiograph is to be recorded. The electrical circuits, and the arrangement as well as construction of the switches, are within the skill of those in the art and accordingly, this subject matter is not illustrated in detail or further described.

The compartment 17 is preferably lined, sides and bottom, with lead plates 61 to afford as added protection against the radiation of X-rays outside the area protected by the sheets 34 and 38 of lead glass in screen frame 30 and cassette 31, respectively. The lining 61 also serves to avoid damage by the primary X-ray beam should the apparatus be inadvertently turned on when neither the screen frame or cassette with their lead glass sheets are in position below platform 14.

It will thus be seen that I have provided a cabinet embodying X-ray apparatus for directing the X-ray beam to a platform of the cabinet on which a person may place his feet while he and others, e. g., an instructor, observe through conveniently-arranged viewing apertures in the top of the cabinet, a reflection of a fluoroscope of the feet registered on a screen removably carried below the platform, and adapted for substitution by a cassette containing film on which may be recorded a radiograph of the foot structure, suitable means being included for changing the electrical circuit through the X-ray apparatus to meet the requirements of fluoroscopy or radiography, respectively, and to indicate by a visible signal the circuit closed.

While I have illustrated and described but one embodiment of my invention, it will be understood that numerous changes in size, design, proportion, and number of the different parts may be made, and particularly that the line of vision may be altered in various ways by the rearrangement of the viewing apertures and reflector 41, as well as by the provision of additional reflectors suitably placed to direct the light rays from the fluorescent screen to the apertures, without departing from the spirit of my invention as defined by the appended claims.

What I claim and desire to secure by Letters Patent is:

1. In a device of the character described, a compartment comprising sides and a top, X-ray apparatus, means to support said X-ray apparatus laterally of the area above the top of the compartment and in a position to direct a beam against said top, a cassette, the entire area above the portion of said top to which the beam is directed being unrestricted whereby a person standing on said portion of the top may see his feet without moving, one of the sides of said compartment having a slot therein for the reception of said cassette into said compartment, means in said compartment adjacent said slot to support said cassette in said compartment below said top.

2. In a device of the character described, a cabinet comprising side walls and a top, said top having a viewing aperture therein, a platform

comprising a part of said cabinet, X-ray apparatus, means to support said X-ray apparatus in said cabinet in a position to direct an X-ray beam downwardly against said platform, a screen below said platform, and a single mirror to reflect light rays radiating from said screen to said viewing aperture, said mirror being disposed in the cabinet to register an image thereon with the different parts of the image in the same relative position with respect to the side walls of the cabinet as the parts of the image registered on said screen.

3. In a device of the character described, a cabinet comprising side walls and having a platform extending laterally from adjacent the bottom thereof, X-ray apparatus and means to mount the X-ray apparatus in the cabinet to direct an X-ray beam through one wall of the cabinet and downwardly onto the platform, the area above said platform being unrestricted to enable a person to see his feet while standing on the platform with his feet within the X-ray beam, a screen-holder and a screen carried in said holder, means to slidably support said holder and screen below said platform, and means to reflect light rays radiating from said screen to a point adjacent the top of the cabinet.

4. In a device of the character described, a housing having a substantially horizontal platform associated with one side thereof, a screen adapted to fluoresce under X-ray excitation disposed under said platform and substantially parallel therewith, X-ray apparatus supported and arranged in said housing to direct an X-ray beam downwardly onto said platform and said screen, the area of the platform to which said beam is directed being disposed laterally of the entire housing.

5. In a device of the character described, a cabinet having a platform extending from one side thereof, X-ray apparatus supported in said cabinet to cast an X-ray beam onto said platform, said cabinet having a viewing aperture therein, a fluorescent screen, means to support said screen below said platform, means to reflect light rays radiating from the screen to said viewing aperture, said platform and cabinet being arranged to afford a person standing on said platform an unrestricted line of vision to, selectively, his feet, and through said viewing aperture to said last-named means.

6. In apparatus of the character described, a cabinet comprising an upright portion and a platform, a fluorescent screen below said platform, a viewing aperture in said cabinet, reflecting means in said cabinet to reflect light rays radiating from said screen to said viewing aperture, and X-ray apparatus in said cabinet at the opposite side of the line of vision extending between said viewing aperture and said reflecting means with respect to the platform to direct an X-ray beam through said platform to said screen.

7. In a device of the character described, a cabinet having a platform extending from one side thereof, X-ray apparatus supported in said cabinet to cast an X-ray beam onto said platform, said cabinet having a viewing aperture therein, a fluorescent screen, means to support said screen below said platform, means to reflect light rays radiating from the screen to said viewing aperture, means comprising a part of said cabinet forming passages for light rays radiating from the screen to the viewing aperture

and from the portion of the top of the platform to which said X-ray beam is directed to a point directly above said last-named portion of the platform.

8. In a device of the character described, a cabinet having a substantially vertical wall and a top, a substantially horizontal platform connected to and extending laterally from said wall, a fluorescent screen below the platform, X-ray apparatus within said cabinet spaced from said wall to provide a light passage between said aperture and said wall and arranged to cast an X-ray beam downwardly onto said platform adjacent said wall and to the screen, said top having a viewing aperture therein adjacent said wall, and means to reflect light rays radiating

from said screen through said light passage to said viewing aperture.

9. In a device of the character described, a cabinet, means having a lead backing disposed at one side of said cabinet against which the subject-matter to be examined is to be disposed, a screen adapted to fluoresce under X-ray excitation disposed between said means and backing and substantially parallel therewith, X-ray apparatus within said cabinet, means to support said X-ray apparatus within said cabinet in a position laterally of all lines passing through and perpendicular to the screen and to direct an X-ray beam to said screen through said first-named means.

ELMER JARED BLISS.
